GARMENT STRETCHING AND PRESSING
MACHINEIrving Primus, Forest Hills, N. Y., assignor to
Isidor Gerber, Brooklyn, N. Y.

Application December 29, 1945, Serial No. 638,073

5 Claims. (Cl. 223—78)

1

The invention relates to machines for stretching and pressing garments such as gloves, stockings or the like, and relates particularly to the means for clamping and stretching and thereby at least partially pressing the garment, and also to the means for pressing protruding parts such as a glove thumb. In what follows, the description will be limited to the application of the invention to a glove and to the thumb and fingers thereof, though it will be understood that the invention is applicable to any garment adapted to be stretched and heated and thereby pressed into the desired wrinkle-free form, or having a part thereof initially extending laterally from the remainder of the garment and intended to be flattened or pressed into the general plane of the garment free of wrinkles.

In prior glove pressing machines such as are shown for example in Patent No. 2,286,059, pressing of the thumb has been attempted by guiding the thumb into a position whereby it may be pressed between pressing rolls, the thumb being stroked or beaten by rotating members at the same time as it is guided, to maintain it in position for pressing. While operative, such machine does not produce the fine and uniform work desirable, since the thumb is not always brought into the proper position to be smoothly pressed or flattened against the palm.

In prior glove turning machines such as are shown in Patents Nos. 2,286,057 and 2,086,058, the glove is turned by grippers clamped upon the wrist end of the glove after the fingers and thumb have been tucked into suitable tubular forms. Linear movement of the grippers turns 35 the glove and simultaneously mounts it right side out on a heating form, from which the glove is later stripped and pressed, there being extensible rods projectable from the heating form for initiating the stripping action or for tucking in the fingers and thumb before the glove is turned.

This invention being intended for use with certain of the mechanisms of said prior Patents Nos. 2,286,057, 2,286,058 and 2,286,059, reference is hereby made thereto for the full disclosure of 45 turning, heating and glove advancing mechanisms not shown in detail herein.

The present invention contemplates the provision of means for mounting a turned glove on to a glove heating form, for clamping one end part of the glove after the turning operation and for stretching the glove by extensible parts at the other end part of the form while the glove remains clamped on the form.

The invention further contemplates the pro-

2

vision of means for moving the glove thumb against the palm in such a manner that the thumb is adequately flattened free of wrinkles and is held flattened and folded under heat and pressure long enough to impart a permanent set thereto sufficient to attain accurate and uniformly dependable pressing thereof, regardless of whether or not a subsequent pressing operation is performed upon the glove.

The invention further contemplates the provision of thumb positioning and pressing means movable outwardly along the thumb, laterally toward the palm and transversely across the palm simultaneously, thereby to carry the glove thumb into the desired flattened and folded position wherein it lies in the general plane of the remainder of the glove and between the center line and the adjacent side edge of the glove, the final part of the movement of said means taking place while the wrist end of the glove is clamped against the heating form on which the glove is mounted.

The various objects of the invention will be clear from the description which follows and from the drawings in which

Fig. 1 is a front elevational view partly in section of the heating forms and of the stretching, pressing and thumb straightening mechanism, only one of the forms being shown substantially in full and the others being shown in part.

Fig. 2 is a fragmentary front elevational view of the operating mechanism carried by each of the forms.

Fig. 3 is a top plan view of the same.

Fig. 4 is a front elevational view of a glove as it appears mounted on a form and clamped just prior to the thumb straightening and glove stretching operations, showing the clamping and straightening plates and a typical projecting position of the thumb assumed thereby after turning of the glove.

Fig. 5 is a similar view of the same, showing the glove stretched and the thumb straightened and pressed against the palm.

Fig. 6 is a fragmentary sectional view of a modified form of the finger and palm stretching means, wherein said means comprises continuations of the stretching rods passing through openings in the relatively fixed parts of the form.

In the practical embodiment of the invention shown by way of example, a series of hollow glove heating forms as 10 (Fig. 1) are mounted for intermittent rotary movement with a shaft 11, which is operated by a suitable Geneva movement such as the Geneva wheel 12 on said shaft.

engaged at intervals and rotated by the Geneva pin 13 carried by the disc 15 on the drive shaft 14 which is driven by power obtained from any suitable source not shown. Since all of the forms and the mechanisms carried thereby are substantially identical, a description of one will suffice for all.

While the form is in the horizontal position shown at the left of Fig. 1 and stationary, suitable turning mechanism removes the glove 16, which is in inside out position on the turning form 17 (Fig. 5), from said turning form and mounts it in right side out position on the heating form 10. The turning mechanism consists of the jaws 18, 19 which grip the wrist of the glove between them at the proper time and move horizontally toward the right to mount the glove on the form 10, as shown by the dash-dot lines indicating the positions of the grippers at the beginning and at the end of the strokes thereof. The operating mechanism for the grippers being fully disclosed in said Patent No. 2,286,059, reference is made thereto for the full description thereof. After the glove has been fully turned and mounted on the heating form, the palm clamps 20 are moved toward the palm and clamp the glove tightly against the form. The thumb straightener 21 is simultaneously moved in the same direction to start the straightening of the thumb and is also moved outwardly of the form and also transversely toward the center of the form to stroke the thumb into its proper folded position against the palm. At the same time, the rods 22, 23, 24 and 25, slidably mounted within the form, are moved outwardly to tension the finger tips of the glove and to move them a sufficient distance longitudinally and away from the palm clamp 20 to stretch the glove to the desired extent and thereby to press it (Fig. 5), the glove being maintained in its stretched and clamped position and meanwhile being heated until it reaches the stripping position shown at the lowermost part of Fig. 1.

As best seen in Fig. 1, in which the usual cover plate for the form 10 has been omitted to expose the parts which otherwise would not be seen, a heating plate 26 is arranged in the interior of the form and is heated by a suitable heating element which also heats the form, said element being electrically connected to a suitable source of current by the wires 27, 28 passing through the form and the hub branch 29 on which the form is mounted. The wires also pass through the shaft 11 and are connected to a suitable commutator not shown such as is disclosed for example in Patent No. 2,148,403, the wires rotating with the shaft, hub branch and form as a unit.

The hub branch supports 29 for carrying the forms are each made hollow to receive the inner end portions 30 of the form, and each branches radially from the sleeve 31 (Fig. 3) which is integral therewith and which is secured to the shaft 11 for rotation therewith. To removably clamp the form to the branch, each branch is split longitudinally along one side thereof and the split parts are tightened about the end 30 of the form by a suitable bolt or the like 32. Passing through said end part 30 and through the branch 29 is the main operating rod 33 reciprocating within the form and carrying the compression spring 34, which abuts at its left end as viewed in Fig. 1 against the shoulder 35 and at its right end against the washer 36 fixed to the rod, whereby the rod is urged toward the right by the spring. At its left end, the main rod 33 carries the cross

bar 37 on which are mounted the stretching rods 22, 23, 24 and 25 sliding respectively in the fingers 38, 39, 40 and 41 of the form. As shown in Fig. 1, the entire tip of each form finger is secured to one of the corresponding stretching rods, whereby movement of the main rod 33 moves the finger tips 42, 43, 44 and 45 outwardly to the dash-dot position thereof indicated.

It will be understood however, that the finger tips may be made integral with the remainders of the form fingers respectively and drilled to permit sliding of the stretching rods therethrough. This form of the invention is shown in Fig. 6, wherein the rods 46, 47, 48 and 49 slide within and are extensible beyond the fixed tips of the form 50 to perform the stretching operation, but when the rods are retracted, the outer ends thereof are flush with the fixed tips. This structure is advantageous where the glove is of such material and size as to be likely to stick or adhere so comparatively tightly to the form as to resist normal stripping of the stretched glove therefrom, in which case the full size finger tips as 42 may not at the proper time be freed of the finger tips of the glove.

The main rod 33 is reciprocated by the fixed cam 51, connected by the member 52 to a fixed part such as the frame 53 of the machine (Fig. 3). The cam roller 54 operated by the cam 51 is pivoted as at 55 to the support member 56 which is secured to the main rod as at 57. As the shaft 11 begins its rotation to carry the forms out of the positions thereof shown in Fig. 1, the roller 54 rides up on the cam and moves toward the left as viewed in Figs. 1, 2 and 3, thereby moving the support member 56, the main rod 33, the bar 37, the stretching rods and the finger tips in the same direction to extend said tips and to stretch the glove, which has previously been clamped to the form by the palm clamps.

Said palm clamps are not moved longitudinally, but are oscillated toward and away from the palm. One of the clamps is provided on each side of the form 10, both clamps being operated in unison. Each of the palm clamps 20 is preferably knurled on its inner surface to grip the glove material firmly, one of the palm clamps 20 being secured as at 61 to the lever 62 which is pivoted to the hub branch 29 as at 63 (Figs. 2 and 3) the other clamp 20 being secured as at 61' to the lever 62' pivoted at 63'. To operate the levers 62 and 62' simultaneously and thereby to clamp the glove on both of its faces to the form, the bell-crank lever 64 is pivoted as at 65 to the branch 29, one arm of said lever 64 carrying the cam roller 66 and a second roller 67, while the other arm carries a third roller 68, said rollers 67 and 68 being at about the same distance on each side of the pivot 65. The cam roller 66 is operated by the bevelled end 69 of the fixed cam 70 at the proper time to rotate the lever 64 in a clockwise direction as viewed in Fig. 3, said cam 70 being suitably secured to the fixed cam 51. On such rotation of the lever 64, the roller 67 thereon rides up on the bevelled cam 71 secured to the lever 62 and the corresponding roller 68 rides up on the similar bevelled cam 72 fixed to the other lever 62', thereby moving the levers 62 and 62' toward each other and toward the form to clamp the glove between the clamps 20 and the form. To urge said levers toward their normal positions in lateral spaced relation to the form, the compression spring 73 is mounted between said levers on the pins 74 projecting therefrom.

It will be understood that the thumb plates 21 are moved toward the form together with the levers 62 and 62', though also having a longitudinal and a transverse movement relatively to said levers. This is accomplished by pivotally securing the right hand end of each of the thumb plate carrying members 75 to a lever 16 as at 11, and pivoting the levers 76 as at 79 and 80 respectively to the support members 56 and 78 respectively, both of the members being suitably secured to the main rod 33 and to each other for movement as a unit. Obviously, the members 56 and 78 and the levers 76 carried thereby move longitudinally together with the main rod 33 and carry the members 75 and the plates 21 secured to said members, with them, to extend said members and to move the plates 21 longitudinally along the glove thumb which may be crooked or protruding laterally at the time. If the thumb is out of position, it is thereby straightened.

The transverse movement of the plates is attained through the cam projection 81 on each member 75 (Fig. 2). Said projection is engaged by the relatively fixed roller 82 on the lever 62 or 62' as the members are extended thereby causing the roller to ride up on the high part of the projection and swinging said members 75 toward the center line of the palm about the pivots 71 and against the action of the springs 83, one of which is secured to the lever 62 and the other to the lever 62' and which urge the members 75 outwardly or away from the center line of the palm. Such movement of the members 75 and the plates 21 carried thereby straightens the glove thumb and folds it inwardly toward the center of the palm, regardless of whether the glove is a right hand glove or a left hand one.

To clamp the thumb against the palm, the member 75 passes through and slides in the groove 84 between the outstanding lug 85 at the left end of each of the levers 62 and 62' and the plate 20 adjacent thereto, whereby movement of said lever about its pivot also swings the member 75 and the support lever 76 therefor about its pivot 79 or 80 during the longitudinal movement and transverse movement of said member into the position shown in Fig. 5.

It will be noted that the clamping, stretching and thumb straightening operations begin as the form is rotated out of the glove mounting position thereof and that the glove remains stretched and heated for about three quarters of a revolution of the shaft 11, whereafter the cams 51 and 70 become effective to permit the rollers to ride off the high parts thereof. The various springs above described then become operative to restore the clamping, stretching and thumb straightening parts to the initial inoperative positions thereof ready for the repetition of the operations on the next glove to be mounted on the form. When the tips 42, 43, 44 and 45 or the rods 46, 47, 48 and 49 are retracted, the stretched and set finger tips of the glove nevertheless overhang the finger tip end of the form and the thus loosened finger tips are easily gripped or operated upon by suitable stripping mechanism to strip the glove off the form at the station just prior to the glove mounting station, the glove and the thumb thereof being released from the clamping mechanism at the stripping station.

It will further be noted that while the stripping mechanism, such as is shown in the prior patents above referred to, may be effective to perform a final pressing operation upon the glove, the larger part if not all of the pressing, that is, free-

ing the glove of wrinkles and shaping it to its required substantially flat form, is accomplished by the comparatively prolonged stretching of the glove while it is heated, so that the final pressing operation may in most cases be dispensed with if desired.

It will also be seen that I have provided means for adequately accomplishing the difficult straightening and pressing of the thumb of either 10 left hand or right hand gloves, first by properly positioning or folding the thumb and second by maintaining it folded under heat and pressure for a comparatively prolonged period.

Various obvious changes may be made in the 15 specific mechanism shown and described without departing from the spirit of the invention defined in the appended claims.

I claim:

- 20 1. In a glove pressing machine, a heating form, means for turning and mounting a glove on the form, means for stretching the mounted glove including means for clamping one end part of the glove against the form and means for tensioning and extending the other end part of the 25 glove, and a thumb straightening and clamping member extensible as a unit with the glove tensioning means.
2. In a glove pressing machine, a heating form provided with fingers, means for rotating the 30 form bodily about a remote axis, means for clamping the wrist end part of a glove to the form comprising a pivoted plate and means including a fixed cam for swinging the plate toward and from the form at predetermined intervals on 35 the rotation of the form, and means sliding longitudinally in the form and extensible beyond the form fingers to engage and move the finger tips of the glove away from the clamping means to stretch the glove.
3. In a glove pressing machine, a heating form provided with fingers, means for intermittently 40 rotating the form through a predetermined part of a revolution, means for clamping the wrist end part of a glove to the form, means sliding longitudinally in the form and extensible beyond the 45 form fingers to engage and move the finger tips of the glove away from the clamping means to stretch the glove, means for releasing the clamping means at the end of said part of a revolution, and means for retracting the stretching means 50 from the finger tips of the glove at the end of said part of a revolution to free the stretched finger tips whereby the freed finger tips are in 55 position to be gripped by suitable stripping mechanism after said rotation.
4. In a glove pressing machine, a form, cam-operated and spring-pressed means for clamping a glove to one end part of a form, and cam-operated and spring-pressed means for moving the other end part of the glove away from the 60 clamping means while the glove remains clamped thereby to stretch the glove and for retracting the glove moving means after a predetermined interval.
5. In a glove pressing machine, a form, means 65 for clamping a glove to one end part of the form, means for moving the other end part of the glove away from the clamping means while the glove remains clamped thereby to stretch the glove and for retracting the glove moving means after a predetermined interval, a thumb straightening and pressing member carried by the glove end moving means, and means for moving said member and said glove end moving means toward 70 75

and from the palm of the form at predetermined intervals.

IRVING PRIMUS.
